UNITED STATES PATENT OFFICE.

POWELL RADER, OF GEORGETOWN, TEXAS.

ROCK-DRILL.

SPECIFICATION forming part of Letters Patent No. 355,278, dated December 28, 1886.

Application filed May 12, 1886. Serial No. 201,987. (No model.)

To all whom it may concern:

Be it known that I, POWELL RADER, a citizen of the United States of America, residing at Georgetown, in the county of Williamson 5 and State of Texas, have invented certain new and useful Improvements in Rock-Drills, of which the following is a specification, reference being had therein to the accompanying drawings.

10 This invention pertains to certain new and useful improvements in bits for rock-drills; and it consists in the peculiar formation of the bit, whereby the drilling operation is more efficiently performed than heretofore, substantially as hereinafter fully set forth, and particularly pointed in the claims.

In the accompanying drawings, Figure 1 is a view in side elevation of my invention. Fig. 2 is a front or plan view of the cutting-edge 15 thereof; and Figs. 3 and 4 are similar views of modifications.

20 In carrying out my invention, I employ the bit A, having a preferably rectangular shank, and on either side face thereof I form a curved recess, C, which recess starts on the right-hand end of each side of said face and gradually deepens toward the left-hand lateral edge of said bit, at which point is formed a passage-way or groove, d, the purpose of which will appear 25 further on.

30 Upon the extreme lower end of the bit is formed a zigzag blade-edge, D, connecting with notches E, formed in said end, which notches are alternately arranged thereon, causing the blade-edge to present an approximately inverted-V shape in side elevation. The blade-edge and notches are arranged on an inclined plane extending from the upper left-hand corner to the lower right-hand corner thereof.

35 In operation the rock débris will be removed 40 by the impact of the curved recesses C there-

on, said débris first passing along the passage-ways or grooves d, thence up along the sides of the bit in the recesses formed therein.

In Figs. 3 and 4 I have shown modified forms 45 of the cutting-edges of my bit, by the employment of which the same object is accomplished as by the employment of the before-described device.

I am aware that it is not new to provide 50 rock-drill bits with an inclined base having a number of cutting-ribs terminating in corresponding ribs on the cutting-edge, also a rock-drill having a straight cutting-edge and twisted cheeks arranged diagonally on opposite faces and terminating in said cutting-edge; but my invention is designed as an improvement 55 over such devices, by means of which I produce a device that is simple, cheap, and in every way durable.

60 Having thus fully described my invention, what I claim, and desire to secure by Letters Patent, is—

1. In a bit for rock-drills, the combination, with the bit having the inclined cutting-edge 65 extending diagonally from one end to the other and the curved recesses formed in the sides of the bit, of the passage-ways or grooves at either end of said cutting-edge opening into the said recesses, substantially as shown and 70 described.

2. The combination, with the bit having the curved recesses in either face thereof, of the cutting-edge having blades and recesses and the passage-ways or grooves, substantially as 75 shown and described.

In testimony whereof I affix my signature in presence of two witnesses.

POWELL RADER.
